UNITED STATES PATENT OFFICE.

WILLIAM SMITH GRAY, OF MAY, TEXAS.

MECHANICAL POWER.

SPECIFICATION forming part of Letters Patent No. 297,595, dated April 29, 1884.

Application filed February 2, 1884. (No model.)

To all whom it may concern:

Be it known that I, WILLIAM SMITH GRAY, a citizen of the United States, residing at May, in the county of Brown and State of Texas, 5 have invented a new and useful Mechanical Power, of which the following is a specification, reference being had to the accompanying drawings.

Figure 1 is a view in perspective of a machine embodying my improvements. Fig. 2 is a view of the machine when used as a stump-puller, mounted on a farm-wagon ready to be transported from place to place. Fig. 3 is a view of the machine removed from its frame, 15 and provided with a base and top bar, where-by it is converted into a simple hoisting-machine. Fig. 4 is a view showing the machine extended, and Fig. 5 is a view showing the lifting-pawls and holding-pawls out of engagement with their respective racks.

This invention has relation to mechanical powers designed for stump-pulling, hoisting heavy weights, &c.; and it consists in the construction and novel arrangement of parts, as 25 will be hereinafter fully described, and particularly pointed out in the claims appended.

Referring by letter to the accompanying drawings, *a* designates the main or center bar of the machine, to the lower end of which is pivoted the cross-head *b*, provided with sockets *c c*, for the reception of the removable wooden levers *d d*. These wooden levers *d d* are perforated in their upper edges at *d'*, and are provided with pins *d''*, secured thereto by chains 30 *d''*, to prevent them from being lost. These pins are employed to hold the wooden levers in place in their sockets. The wooden levers may vary in length in order to vary the power according to the requirements when the machine 35 is used. The cross-head *b* has spaces *e e*, in which the lifting-pawls *f f*, with their handles *f' f'*, are fulcrumed, the handles extending above the cross-head and the lifting-pawls *f f* below the same. The lifting-pawls *f f* are 40 rectangular in form and engage the teeth *g* on the inner edges of the rack-bars *h h'*. The rack-bars *h h'* are connected at their lower ends by the parallel bars *i i*, secured thereto by pivot-bolts *i'*, and they carry between them the 45 pivoted eye *i''*, to which the log-chain is to be attached when the machine is to be used as a

stump-puller. The upper ends of the rack-bars *h h'* are also provided with pivot-bolts *i'*, by which parallel bars *i i* may be secured thereto when the machine is to be used as a 55 simple hoisting-machine.

A short distance above the cross-head *b* are the check-pawls or holding-pawls *k k'*, which are pivoted to the center bar, *a*, and normally engage the teeth in the outer edges of the rack-bars *h h'*. Above these holding-pawls *k k'* are two parallel arms, *l l*, rigidly secured to the center bar, *a*, and provided near each end with swinging hooks *n n*, to hold the check-pawls *k k'* up out of engagement with the rack-bars *h h'* when it is desired to lower the rack-bars *h h'* to begin the pull.

Where the machine is to be used for pulling stumps, it is mounted on a portable derrick, *p*, that may be either drawn on runners as a sled 60 or mounted on the bolsters of a farm-wagon, in the following manner: The machine is suspended from the top of the derrick *p* by a pivotal connection, as at *q*, the derrick being suitably braced, as at *r*. The four posts *r'* are 65 each provided with a perforated stirrup, *s*, on their outer sides, and the posts also have holes aligned with the perforations in the stirrups *s*. Four levers, *s'*, are fulcrumed to clips *s''*, and connected by chains *s''* through their ends to 70 bails pivoted to the ends of the runners. These levers *s'* are also provided each with a chain, 75 *s''*, having a pin at its end to secure the lever in its stirrup. To support the frame or derrick *p* on the wagon, the clips *s''* are placed 80 over the wagon-bolsters or over false bolsters, and secured by pins. The power ends of the levers *s'* are then pressed down into their respective stirrups to raise the derrick from the ground, and the pins inserted into the proper 85 perforations to hold it in the elevated position. It may then be transported to the next stump and let down upon the ground for use. The wooden lifting-levers operate the lifting-pawls alternately, and thereby raise the rack-bars *h h'* alternately, and the holding-pawls 90 engage the outer teeth of the rack-bars and hold them until the next lift on the bars, when they will be again raised and held, and this operation is repeated until the rack-bars have 95 been elevated to the desired height.

When the machine is to be used simply as

a hoisting-machine—that is, where it is to be placed under an article to lift it—it is removed from the derrick and the center bar is provided with a base, *u*, and a cross-head, *v*, is to be provided at the upper ends of the rack-bars *h h'*, as shown. In other respects the machine is the same as that hereinbefore described. When used as a stump-puller, it should be replaced in its derrick, the eye *w* and key *x* being employed to secure it in place. A machine of this construction possesses great strength and an immense amount of power can be applied through it, enabling two men to remove the largest stumps and to 15 hoist heavy articles with comparative ease. It is cheap, simple, and durable, is not likely to get out of order, and may be easily transported and operated.

Having thus fully described my invention, 20 what I claim as new, and desire to secure by Letters Patent of the United States, is—

1. As an improvement in mechanical powers, the combination, with the center bar having a pivoted cross-head at its lower end carrying two lifting-pawls, and two holding-pawls pivoted to the center bar above the cross-head, of two rack-bars working through the lower cross-head on the center bar and through a cross-head above the holding-pawls, and two 25 levers for operating the pivoted cross-head and lifting-levers, substantially as specified.
2. In a mechanical power, the combination, with the center bar, pivoted cross-head, and rigid cross-head thereon, and the rack-bars, 30 lifting-pawls, and holding-pawls, of the swinging hooks at the ends of the rigid cross-head on the center bar, for engaging the holding-pawls and keeping them out of engagement with the racks, substantially as specified.

3. In a mechanical power, the combination, 40 with the center bar and rack-bars and the lifting and holding pawls, of the pivoted cross-head having end sockets for the reception of the removable wooden levers, substantially as specified.

4. In a mechanical power, the combination, 45 with the derrick, the posts of which are provided with the perforated stirrups, of the levers having clip-fulcrums, and chains provided with securing-pins connected at their power ends by chains to the runners of the derrick, substantially as specified.

5. In a mechanical power, the combination, 50 with the pivoted cross-head at the lower end of the center bar, the rigid cross-head on the center bar, and the rack-bars connected by pivoted parallel bars at their lower ends, of the hold-pawls below the rigid cross-bar and the lifting-pawls pivoted in spaces in the pivoted cross-head on opposite sides of the center bar and provided with lever-handles, substantially as specified.

6. In a mechanical power, the combination, 55 with the center bar provided with a base, a pivoted cross-head, a rigid cross-head, and 60 lifting-pawls and holding-pawls, of the rack-bars having upper and lower pivoted cross-heads, substantially as specified.

In testimony that I claim the foregoing as my own I have hereto affixed my signature 70 in presence of two witnesses.

WILLIAM SMITH GRAY.
